TOY ENGINE STARTER EMPLOYING ELASTIC ELEMENT

Josiah Morrison Barr, Manhattan Beach, Calif., assignor, by mesne assignments, to Wen-Mac Corporation, Los Angeles, Calif., a corporation of California

Application February 5, 1958, Serial No. 713,414

9 Claims. (Cl. 185—41)

This invention relates to a starter for a small internal combustion engine such, for example, as employed to power toy aircraft, etc. Although the starter is useful in connection with engines for propelling toy boats and vehicles, it is of especial utility as a simple and effective starter for the internal combustion engines of toy aircraft having a revolvable impeller. The starting of toy engines of this type requires a rapid spinning of the engine shaft in forward direction which is difficult to attain by application of a finger of the operator to the airplane propeller to rotate the same.

It is an object of the invention to provide a toy engine starter wherein the force for rotating the engine shaft forwardly is derived from a simple and inexpensive elastic member which may be a rubber loop, such as a rubber band or a rubber ring commonly known as an O-ring. The invention provides means for connecting a portion of the elastic member to the engine, in such position that when it is not in use for starting purposes it will be retracted, and therefore, spaced from the revolving propeller. The invention provides means for connecting another portion of the elastic member, referred to as the front portion or front end eccentrically to the crankshaft of the engine so that as the crankshaft is revolved in reverse direction, the forward portion of the elastic member will be wound around the shaft and force will be built up in the elastic member as it is stretched tending to revolve the shaft in forward, engine starting, direction. When the rearward rotational force is thereafter released from the shaft so that the shaft is free to turn in the forward direction, the tension in the stretched elastic member will act to revolve the shaft in forward direction with such rapidity that the engine shaft will be caused to spin through a number of complete revolutions, effecting a number of compression cycles of the piston of the engine which will quickly start the engine providing that the other factors of fuel mixture and ignition are present.

It is an object of the invention to provide a toy engine starter having an elongated member at least a portion of which is elastic and means for detachably connecting a portion of this elongated member to the shaft so that the elongated member will be wound upon the shaft when it is turned in rearward direction.

It is an object of the invention to provide a simple and effective starter for toy engines consisting of a rotatable means such as a spool connected to the shaft so as to rotate therewith, this spool having thereon a projection over which a portion of an elastic loop may be hooked, there being means for connecting another portion of the loop to the engine so that as the spool is rotated in reverse direction the elastic loop will be stretched as a portion of it is wound around the spool, the force exerted by the elastic loop in attempting to return to its initial, relaxed state, effecting starting rotation of the spool and the engine shaft to which it is connected.

Further objects and advantages of the invention will be brought out in the following specification wherein details have been explained for the purpose of disclosure, without

2

intending to limit the scope of the invention which is defined by the appended claims.

Referring to the accompanying drawings which are for illustrative purposes only:

5 Fig. 1 is an enlarged elevational view of a toy engine equipped with the invention in dormant condition;

Fig. 2 is an elevational view similar to Fig. 1 but showing the initial step of detachably connecting the elastic member to the spool which is mounted on the engine shaft;

10 Fig. 3 is a sectional view taken as indicated by the line 3—3 of Fig. 2;

Fig. 4 is an elevational view of the engine with the forward portion of the elastic member wound on the spool;

15 Fig. 5 is a face view, to reduced scale, of the elongated elastic member of the invention.

In Fig. 1, I show a toy internal combustion engine 10 having a crank mechanism 11 comprising a disc 12 having a projecting crankpin 13 which engages the lower end of the connecting rod 14 of the engine, to correlate the reciprocation of the piston, not shown, with the rotation of the disc 11. From this crank mechanism a shaft 15 extends outwardly through an opening 16 in the crankcase 17 of the engine 10 for transmitting rotation to the part which is to be driven. In the present disclosure, the engine 10 drives a toy propeller 18 which is fixed on the end of the shaft by a nut 19. The invention provides an elongated member 20, at least a portion of which is elastic, so that the member 20 may be stretched longitudinally.

20 In the form of the invention disclosed the member 20 is a band or loop of rubbery substance, such as a rubber compound. For convenience, the elastic member 20 is obtained in the form of a rubber ring known to the trade as an O-ring and has the appearance shown in Fig. 5. The engine 10 has thereon a mounting flange 21 to which the rear portion 22 of the flexible member 20 is connected by a plate 23 which is connected to the flange 21 by a screw 24 and has spaced notches 25 through which adjacent parts of the rear portion 22 of the member 20 are passed, supporting the member 20 so that its front end or portion 26 is in retracted position. That is to say, the front end 26 of the member 20 is positioned rearwardly of the plane in which the blades of the propeller 18 rotate, and therefore, will not interfere with the rotation of the propeller.

25 The invention provides means 27 for detachably connecting the front end 26 of the elastic member 20 to the shaft 15 in such a manner that rotation of the shaft 15 in reverse direction will wind a portion of the member 20 around the shaft as will be later described. The connecting means 27 includes a spool 28 which is fixed on a projecting portion of the shaft 15 contiguous to the front end of the engine 10. A pin 29 projects outwardly from the peripheral face of the spool 28 between the flanges 30 thereof. This pin 29 provides a projecting member over which the front end 26 of the band or loop 20 may be placed as shown in Figs. 2 and 3.

30 To accomplish this initial step in the operation of the starter, the propeller 18 is rotated from the position in which it is shown in Fig. 1 through an angle of approximately 90° into the position in which it is shown in Figs. 2 and 3. The operator then pulls the end 26 upwardly from the position in which it is shown in Fig. 1 into the position in which this end portion 26 is shown in Figs. 2 and 3 whereupon the end portion 26 is placed over the pin 29, making such engagement therewith that when the propeller 18 is rotated by hand in reverse (clockwise) direction the end portion 26 of the member 20 will be carried around the peripheral face 31 of the spool 28 as the position of the pin 29 moves in clockwise direction around the axis of the shaft 15. The operator

manually rotates the propeller 18 in clockwise direction, thereby revolving the spool 28 in clockwise direction, winding the forward portion 32 of the elastic member 20 upon the spool 28, as shown in Fig. 4. Ordinarily the spool 28 will be revolved through one and one-quarter turns in clockwise direction so that the pin 29 will be moved from the position in which it is shown in Fig. 2, to the position in which it is shown in Fig. 4.

The invention also provides guide means 35 engaging an intermediate portion of the member 20 so that the end portion 32 of the member 20 will extend along or approximately coincide with a normal plane projecting through a portion of the spool 28. In Fig. 4, a plane *p-p* is indicated. That portion 32a of the elastic member 20 which extends from the lower extremity of the guide means 35 coincides with this plane *p-p* and the stretched portion of the elastic member 20 is maintained in optimum position for rotating the spool 28 and the shaft 15 in forward direction.

The guide means 35 consist of a stiff wire 37 bent so as to provide a pair of legs 38 and 39, the upper ends of which are secured to laterally projecting flanges 40 which are formed on opposite sides of the engine crankcase 17, and a transverse arched portion 41 having roller means 42 thereon consisting of a short length of plastic tubing which will rotate as the elastic member 20 is pulled thereacross from the position in which it is shown in Fig. 1 to the positions thereof shown in Figs. 2, 3 and 4. When the rearward rotational force, which has been applied to the shaft so as to rotate the same in rearward direction and wind the portion 32 of the elastic member thereon, is released, the tension built up in the member 20 as the result of stretching the same will return the member 20 from the position in which it is shown in Fig. 4 to its retracted position, shown in Fig. 1, and the shaft will be rotated in forward (counterclockwise) direction at relatively high velocity capable of effecting starting of the engine.

I claim:

1. In a starter for an internal combustion engine having a shaft connected to the crank mechanism of the engine: an elongated elastic member; means for connecting the rear end of said elastic member relative to the engine with the front end of said elastic member in retracted position; and detachable engagement means for connecting the front end of said elastic member eccentrically to said engine shaft so that as a rearward rotational force is applied to said shaft and said shaft is thereby rotated in reverse direction, said elastic member will be stretched and a portion thereof wound around said shaft to apply to said shaft a torque which will rotate said shaft in forward, engine starting, direction upon release of said rearward rotational force from said shaft.

2. In a starter for an internal combustion engine having a shaft connected to the crank mechanism of the engine: an elongated elastic member; means for connecting the rear end of said elastic member relative to the engine with the front end of said elastic member in retracted position; rotatable means connected to said shaft; and detachable engagement means for connecting the front end of said elastic member to said rotatable means so that as a rearward force applied to said rotatable means rotates the same in rearward direction, a portion of said elastic member will be wound upon said rotatable means and said elastic member will be thereby stretched and will apply torque to said rotatable means to effect forward, engine starting, rotation thereof upon release of the application of said rearward force to said rotatable means.

3. In a starter for an internal combustion engine having a shaft connected to the crank mechanism of the engine: an elongated member, at least a portion of which is elastic; means for connecting the rear end of said elastic member relative to the engine with the front end of said elastic member in retracted position; detachable engagement means for connecting the front end of said

elastic member eccentrically to said engine shaft so that as a rearward rotational force is applied to said shaft and said shaft is thereby rotated in reverse direction, said elastic member will be stretched and a portion thereof wound around said shaft to apply to said shaft a torque which will rotate said shaft in forward, engine starting, direction upon release of said rearward rotational force from said shaft; and a guide engaging an intermediate portion of said elastic member.

4. In a starter for an internal combustion engine having a shaft connected to the crank mechanism of the engine: an elongated member, at least a portion of which is elastic; means for connecting the rear end of said elastic member relative to the engine with the front end of said elastic member in retracted position; rotatable means connected to said shaft; detachable engagement means for connecting the front end of said elastic member to said rotatable means so that as a rearward force applied to said rotatable means rotates the same in rearward direction, a portion of said elastic member will be wound upon said rotatable means and said elastic member will be thereby stretched and will apply torque to said rotatable means to effect forward, engine starting, rotation thereof upon release of the application of said rearward force to said rotatable means; and a guide engaging an intermediate portion of said elastic member.

5. In a starter for an internal combustion engine having a shaft connected to the crank mechanism of the engine: an elongated member, at least a portion of which is elastic; means for connecting the rear end of said elastic member relative to the engine with the front end of said elastic member in retracted position; a spool connected to said shaft and having forward and rearward rotation; and a projection on said spool with which the front end of said elastic member may be engaged so that rearward rotational force applied to said spool will rotate the same in rearward direction and wind a portion of said elastic member upon said spool, stretching the same so as to produce therein a force tending to rotate said spool in forward, engine starting, direction upon release from said spool of said rearward rotational force.

6. In a starter for an internal combustion engine having a shaft connected to the crank mechanism of the engine: an elongated elastic member; means for connecting the rear end of said elastic member relative to the engine with the front end of said elastic member in retracted position; a spool connected to said shaft and having forward and rearward rotation; a projection on said spool with which the front end of said elastic member may be engaged so that rearward rotational force applied to said spool will rotate the same in rearward direction and wind a portion of said elastic member upon said spool, stretching the same so as to produce therein a force tending to rotate said spool in forward, engine starting, direction upon release from said spool of said rearward rotational force; and a guide engaging an intermediate portion of said elastic member.

7. In a starter for an internal combustion engine having a shaft connected to the crank mechanism of the engine: an elastic member comprising a loop of elastic rubbery substance; means for connecting the rear end of said elastic member to the engine with the front end of said elastic member in retracted position; and detachable engagement means for connecting the front end of said elastic member eccentrically to said engine shaft so that as a rearward rotational force is applied to said shaft and said shaft is thereby rotated in reverse direction, said elastic member will be stretched and a portion thereof wound around said shaft to apply to said shaft a torque which will rotate shaft in forward, engine starting, direction upon release of said rearward rotational force from said shaft.

8. In a starter for an internal combustion engine having a shaft connected to the crank mechanism of the engine; an elastic member comprising a loop of elastic

rubbery substance; means for connecting the rear end of said elastic member to the engine with the front end of said elastic member in retracted position; a spool connected to said shaft and having forward and rearward rotation; and a projection on said spool with which the front end of said elastic member may be engaged so that rearward rotational force applied to said spool will rotate the same in rearward direction and wind a portion of said elastic member upon said spool, stretching the same so as to produce therein a force tending to rotate said spool in forward, engine starting, direction upon release from said spool of said rearward rotational force.

9. In a starter for an internal combustion engine having a shaft connected to the crank mechanism of the engine; an elastic member comprising a loop of elastic rubbery substance; means for connecting the rear portion of said loop to a part of the engine spaced from the front end thereof; a spool connected to said shaft and

5

having forward and rearward rotation; a projection on said spool over which the front portion of said loop may be placed so that rearward rotation of said spool will wind the front portion of said loop thereon, creating in said loop a tension tending to rotate said spool in forward, engine starting, direction; and a guide for said loop disposed in a position between said spool and said means for connecting the rear portion of said loop to said engine, said guide being spaced radially outwardly from said spool so that the portion of said loop which passes from said guide to said spool will lie close to a normal plane which passes through said spool.
